UNITED STATES PATENT OFFICE.

SOLOMON SCHELINSKY, OF NEW YORK, N. Y.

SUPPLEMENTAL WAISTBAND FOR PANTS.

SPECIFICATION forming part of Letters Patent No. 691,006, dated January 14, 1902.

Application filed August 17, 1901. Serial No. 72,323. (No model.)

To all whom it may concern:

Be it known that I, SOLOMON SCHELINSKY, a citizen of the United States, residing at the city of New York, borough of Manhattan, 5 county and State of New York, have invented certain new and useful Improvements in Supplemental Waistbands for Pants, of which the following is a specification.

My invention has relation to supplemental 10 and yielding waistbands which are employed in connection with children's pants for the purpose of permitting the latter to be buttoned to the usual shirt-waist worn by children for the ultimate purpose of avoiding the 15 necessity of using suspenders or the like, the utility of the article being well understood by those skilled in the art.

Prior to my invention it has been customary to build up these supplemental waistbands 20 of strips of fabric secured together with strips of elastic interposed in the direction of their length and so secured to the separate strips of the band that when one to which buttonholes are applied is pulled the elastic will 25 be stretched, the outer strip being secured to the permanent waistband of the pants so as to support them, and by a further arrangement of folded or slack inelastic fabric formed in or by one of the strips or a supplemental piece 30 of fabric the stretch of the elastic is limited—that is to say, after a certain degree of separation of parts the inflexible fabric takes the strain and limits the stretch of the elastic, limiting its extension and relieving it of further strain.

My present invention has mainly to do with what is known as the "back-band," which is secured directly to the permanent band of the pants, as distinguished from that part of 40 the supplemental band which is provided with buttonholes for securing it directly to the shirt-waist.

By a very simple construction I provide a very suitable back-band with elastic strips 45 and the limiting or restraining fabric in an expeditious and economical manner.

My invention therefore resides in the construction and combination of parts herein-after described, and further pointed out in the 50 claim.

I have illustrated my invention in connection with a complete supplementary band, the

parts embodying my invention being particularly pointed out hereinafter.

In the drawings forming part of this specification, Figure 1 is a side elevation of the back-band embodying my improvements. Fig. 2 is a sectional elevation, enlarged, on the line *xx*, Fig. 1. Fig. 3 is a like view showing the operation of the band in use. Fig. 4 is a front elevation of a portion of the buttonhole-band of the usual or desired construction. Fig. 5 is a sectional elevation on the line *yy*, Fig. 4. Fig. 6 is a front elevation of a portion of a complete supplementary waistband 65 embodying my improvements, and Fig. 7 is an enlarged sectional elevation on the line *zz*, Fig. 6.

Similar reference characters indicate like parts throughout the several views.

I shall first describe the construction of the back-band.

I take two strips of fabric, such as muslin or the like, of any desired length or width, as A and B, the upper edge of the upper strip 75 being preferably turned over, as at *a*. The upper edge *b* of the lower strip B is sewed to the face of the upper strip A, preferably midway between the latter's width, as by the line of stitching *c*, leaving the lower overlapping 80 portion *d* of the upper strip A free to form pockets for receiving the elastic and restraining tongue, as hereinafter described. The lower edge *e* of the lower strip B is turned up, as at *e*. At C are the elastic strips consisting of strips of elastic webbing or the like, disposed transversely of the band and inserted between the depending overlapping tongue *d* of the upper strip A and the inturned end *e* of the lower strip B, a line of stitching, 90 as at *f*, securing the elastic strips at their upper edge firmly to the overlapping tongue *d* (only) of the upper strip A. There may be any number of these elastic strips, and in the manufacture of the back-band as a separate 95 and distinct article from the supplementary waistband I prefer not to stitch or secure the lower ends on this strip to the fabric or the band. The elastic strips are stretched by the application of a pull to the tongue *d* of the upper strip A. The tongue also provides means for relieving the strain on the elastic strips and limits their yielding movement.

In Fig. 2 I have diagrammatically illus-

- trated at *g* the point of pull on the tongue *d* of the upper strip *A*, the dotted lines *h* representing the subsequently-attached button-hole-band, and at Fig. 3 I have illustrated diagrammatically the action of the overlapping tongue when power is applied to it through the buttonhole-band, stretching the elastic strips, the uplifting of the tongue limiting such stretching and relieving it of strain.
- 10 Any form of buttonhole-band or like device may be used for connecting the back-band with the buttons on the shirt-waist, the only exception to this being that whatever means are employed it should be secured to the overlapping tongue.

In Figs. 4 and 5 I have illustrated a suitable form of button-band *D*, which consists, preferably, of a single strip of material *i*, bent over upon itself at the top *j* and bottom *k* and the top edge again bent over, as at *l*, to form a beading or edge for strengthening purposes and reducing wear, the upper double-layer portion of the band being provided with buttonholes *m*, worked in any suitable manner, preferably immediately below the beaded upper edge, so that the latter can take the strain off the button.

In Figs. 6 and 7 is illustrated the preferred method of connecting the buttonhole-band 30 and the back-band and the latter's connection with the permanent waistband of the pants. The buttonhole-band *D* is preferably narrower than the back-band, so as to leave the edges *a* and *e* of the latter projecting 35 above and below the former to enable the latter to be stitched at the projecting edges to the permanent waistband *B* of the pants, which is conventionally indicated by dotted lines. As illustrated in Fig. 6, a line of stitching *n* secures the buttonhole-band *E* throughout the entire length of the overlapping tongue *d* of the back-band, and this line of stitching is supplemental to and independent of the stitching *c* for securing the upper and 40 lower strips *A* and *B* of the back-band together. This firmly secures the buttonhole-band to the overlapping tongue of the back-band. It is desirable also to secure the buttonhole-band to the back-band below the over-

lapping tongue of the back-band. This is 50 done by the line of stitching *o*; but instead of stitching the lower edge of the button-band to the lower edge *e* of the back-band at the place where the elastic strips are located I divert the stitching over from the button-hole-band and onto the back-band, as illustrated at *p* in Fig. 6, thereby not only securing in this one operation the overlapping edge of the lower strip *B* of the back-band and the ends of the elastic strips together, but leave 60 the lower edge *k* of the buttonhole-band perfectly free, so as not to interfere with the separation of the buttonhole-band at this point and to allow the elastic strips to expand, which at this time are connected at their upper ends 65 to the button-band and at their lower ends to the lower edge of the lower strip *B* of the back-band. The back-band is secured to the pants-band *E* preferably at the lower edge at *q*, Fig. 7, and at *r* also, if desired. 70

By the foregoing construction I dispense with structures which entail unnecessary stitching and waste of time and labor and produce an efficient article.

Having described my invention, I claim— 75

A waistband for pants, comprising a back-band composed of the two strips *A* and *B* secured together to provide an overlapping tongue *d*, and elastic strips secured to the lower edge of the strip *B*, and to the lower 80 edge of the overlapping tongue and below the point of attachment of the strip *A* to the strip *B*, and a buttonhole-band attached to the lower edge of the overlapping tongue, the lower edge of the buttonhole-band being secured to the lower edge of the back-band, the stitching being intermittent between the place on the back-band where the elastic strips are located, so as to leave the lower edge of the buttonhole-band at this point free of the back- 85 band, as and for the purposes set forth. 90

Signed at the city, county, and State of New York this 15th day of August, 1901.

SOLOMON SCHELINSKY.
